(57) **CLAIM**

The ornamental design for a landscape edging block, as
shown and described.

DESCRIPTION

FIG. 1 is a perspective view of a first embodiment landscape
edging block, in accordance with the present invention;

FIG. 2 is a front view of the landscape edging block shown
in FIG. 1;

FIG. 3 is a rear view of the landscape edging block shown
in FIG. 1;

FIG. 4 is a right side view of the landscape edging block
shown in FIG. 1, the left side being a mirror image thereof;

FIG. 5 is a top view of the landscape edging block shown
in FIG. 1; and,

FIG. 6 is a bottom view of the landscape edging block shown
in FIG. 1.
